UNITED STATES PATENT OFFICE

2,376,091

IMMERSION CONTROL

Burton E. Shaw, Bristol, Ind., assignor to Penn Electric Switch Co., Goshen, Ind., a corporation of Iowa

Application August 11, 1942, Serial No. 454,374

2 Claims. (Cl. 200—138)

My present invention relates to an immersion control of the temperature responsive variety.

One object of the invention is to provide an immersion control including a housing for immersion in a body of liquid or the like and a temperature responsive element in the housing for response to the temperature of the liquid, a liquid fill being provided in the housing for readily conducting heat from the wall of the housing to the temperature responsive element therein.

A further object is to provide a simple arrangement of sealing means for an actuating shaft of a temperature responsive element with respect to the housing so that the liquid fill does not leak out and yet slight oscillating motion of the actuating shaft is permitted, without binding.

Another object is to provide means for adjusting the range of operation of the immersion control comprising a casing oscillatably mounted on the housing and carrying the control device, such as a switch or the like, actuated by the temperature responsive element.

With these and other objects in view, my invention consists in the construction, arrangement and combination of the various parts of my device whereby the objects contemplated are attained, as hereinafter more fully set forth, pointed out in my claims and illustrated in the accompanying drawing wherein:

Figure 1 is a vertical sectional view through an immersion control embodying my invention, the control being illustrated as mounted in the wall of a cooling chamber of an internal combustion engine or the like; and

Figure 2 is a sectional view on the line 2—2 of Figure 1.

On the accompanying drawing I have used the reference numeral 10 to indicate a tube, which is preferably formed of metal. The tube 10 has one end brazed or soldered into a sleeve 12, and the tube and cylinder together constitute a housing for a coiled bimetal element 13. The bimetal element 13 has one end secured, as by a rivet 14, to a bracket 15. The bracket 15, in turn, is anchored by screws 16 to the inner wall of the sleeve 12.

The other end of the bimetal element 13 is secured, as by a rivet 17, to a hub 18 of an actuating shaft 19. The actuating shaft 19 has one end journaled in an end member 20 soldered or brazed into the inner end of the tube 10. Its other end passes loosely through an end member 21 which is soldered or brazed into the sleeve 12. The housing 10—12 is filled with a liquid fill 22, 55

which may be of any suitable liquid for readily conducting heat. For instance, when the immersion control is used in connection with an internal combustion engine the fill 22 may be alcohol or Prestone, so that there is no danger of it freezing in sub-freezing weather.

The sleeve 12 at one end is threaded for the purpose of mounting the control structure in a threaded boss 23 of a cooling jacket 24 of an internal combustion engine or the like. The water within the cooling jacket is illustrated at 25. To prevent the liquid fill 22 from leaking out through the end member 21, I provide a collar 26 mounted in liquid-tight relation to the actuating shaft 19, and a flexible sleeve 27 of neoprene or the like has one end tightly engaged around the collar 26 and its other end tightly engaged around a reduced neck 28 of the end member 21. The sleeve may be vulcanized to the parts 26 and 28 if found desirable, and with this arrangement leakage is prevented, while, at the same time, the actuating shaft 19 may oscillate slightly without appreciable resistance to such oscillation by the sleeve 27.

A casing 29 is oscillatably mounted on the sleeve 12 and carries a control device, such as a switch S. The switch S is not shown in detail in the present application but is fully disclosed in my Patent No. 2,170,341, issued August 22, 1939. The switch S is mounted on a plate 30 having a pair of ears 31 secured, as by screws 32, to the back of the casing 29. The switch S includes an actuating button 33, which is spring extended and adapted to be depressed to the position shown in Figure 2 by the actuating shaft 19.

As an operative connection between the shaft 19 and the button 33 I provide an actuating arm 34 having a hub 35 secured, as by a set screw 36, to the shaft 19. The arm 34 carries an adjusting screw 37 having a head 38 engageable with the button 33. A lock nut 39 is provided for retaining the adjustment.

An adjusting arm 40 is secured to the sleeve 12 and is provided with an arcuate slot 41. An adjusting screw 42 passes through the slot 41 and is threaded into the back of the casing 29. A cover 43 is provided for the casing.

Practical operation

In the operation of my immersion control a rough adjustment for range of operation may be had by loosening the screw 42 and swinging the casing 29 to a new position relative to the sleeve 12. The screw 42 may then be retightened for locking the casing in the newly adjusted position. Thus the position of the switch S with respect

to the actuating arm 34 may be varied. A fine adjustment may then be had by means of the adjusting screw 37.

In operation the actuating arm 34 in one position causes the head 38 of the adjusting screw 37 to depress the button 33 to the position illustrated in Figure 2 for positioning the switch S in one circuit-controlling position. When the bimetal element 13 responds to a different temperature so as to rotate the arm 34 counter-clockwise in Figure 2, the button 33 is released for permitting the switch S to assume its other circuit-controlling position. Thus the temperature affecting the bimetal element 13 at a certain point changes the position of the switch S from open circuit to closed circuit position, and at another point changes the position of the switch from closed circuit to open circuit position. The temperature of the bimetal element 13 closely follows that of the water 25 due to the ready transmission of heat from the water through the metallic tube 10 and the liquid fill 22 to all parts of the bimetal element. Thus the element is very sensitive to slight changes in temperature of the liquid 25, and its response is relatively quick, as distinguished from the slow response of an element not surrounded by a liquid fill.

The fill 22 is effectively sealed in by the tube or sleeve 21, which also eliminates the necessity of a packing gland and the attendant friction. The sleeve 21 forms an inexpensive and simple sealing means when compared with a packing gland.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. An immersion control of the character dis-

closed comprising a metallic housing, a coiled bimetallic element therein, an actuating shaft extending through said housing, said housing having a pair of end members one at each end 5 of the housing in which said actuating shaft is journalled, one of said end members having a sleeve-like extension exterior of said housing, said bimetallic element having one end thereof secured to said actuating shaft adjacent the other of said end members and the other end thereof secured to said housing adjacent said one of said end member, a liquid fill in said housing for facilitating the conduction of heat from a medium exterior of said housing and from the 15 housing to said bimetallic element, a non-metallic flexible sleeve surrounding a portion of said actuating shaft exterior of said housing and having one end sealed relative to said sleeve-like extension and its other end sealed relative to said actuating shaft, and a control device exterior of both said housing and said flexible sleeve and actuated by said actuating shaft.

2. A control of the character disclosed comprising a housing, a coiled bimetallic element 25 therein, an actuating shaft through said housing, said housing having a pair of end members in which said actuating shaft is journalled, one of said end members having a closed end bearing for said actuating shaft, said bimetallic element having one end thereof secured to said actuating shaft adjacent said one of said end members and the other end thereof secured to said housing adjacent the other of said end members, a flexible sleeve surrounding said actuating shaft adjacent said other end member and having one end sealed relative to said last end member, its intermediate portion extending away from said last end member exterior of said housing, and its 35 other end sealed relative to said actuating shaft, and a control device actuated by said actuating shaft.

BURTON E. SHAW.
